UNITED STATES PATENT OFFICE.

CORNELIUS SHEPARDSON, OF CAZENOVIA, NEW YORK.

SWINGING CHAIR.

SPECIFICATION forming part of Letters Patent No. 358,701, dated March 1, 1887.

Application filed November 23, 1886. Serial No. 919,566. (No model.)

To all whom it may concern:

Be it known that I, CORNELIUS SHEPARDSON, of Cazenovia, in the county of Madison, in the State of New York, have invented new 5 and useful Improvements in Swinging Chairs, of which the following, taken in connection with the accompanying drawings, is a full, clear, and exact description.

This invention consists in a novel organization of a swinging chair having its members hinged to each other and connected to suspending-ropes in such a manner as to allow the occupant of the chair to assume either a sitting or reclining posture and automatically 15 conform the chair to said posture.

In the annexed drawings, Figure 1 is a perspective view of my invention in a reclining position, a portion of the cover forming the seat and back being torn away to show the 20 construction of the frame; and Fig. 2 is a side view showing my invention converted into the form of a suspended chair.

Similar letters of reference indicate corresponding parts.

25 A A represent the two side rails of the seat-frame, which rails are connected only at the front by the cross-rail B.

C C are the two side rails of the back-frame, which rails are hinged to the rear ends of the 30 rails A A, and are framed together at their upper ends by a cross-rail, D. The entire space from the said cross-rail to the cross-rail B, at the front of the seat, is devoid of intermediate cross-rails, which feature is important in the 35 operation and use of the combined chair and hammock formed by my invention, inasmuch as the seat and back proper is composed of a single piece of canvas or cloth, or other suitable flexible material, extending from the front 40 cross-rail, B, of the seat-frame to the top cross-rail, D, of the back-frame and tacked onto said cross-rails and onto the side rails, A A and C C, and in throwing the chair into a reclining position or conversely from the latter position 45 to that of a chair, the cloth cover readily conforms to the back of the occupant.

a a represent the side rails of the foot-rest, hinged to the front end of the side rails, A A, of the seat-frame and formed with rearward 50 extensions, d.

b b' are articulated arms, one of which is

rigidly attached to the side rail, a, of the foot-rest and the other arm is pivoted on the side rail, C, of the back-frame, and thus the back is compelled to conform to the movement of the 55 foot-rest.

c c denote side guard-rails, and d a front guard-rail, which latter lies with its ends across the ends of the side guard-rails. All of said guard-rails are perforated at their ends and 60 supported on tubular posts e e, and secured to the seat-frame by the suspending-ropes f f'. There are two sets of suspending-ropes connected to opposite sides of the chair. Each set being composed of three ropes, f, f', and 65 g. The rope f passes through the perforated crossing ends of the aforesaid guard-rails at the front of the seat and through the tubular post e, and loosely through the seat-frame near the front thereof, and is firmly secured to the rear- 70ward projection a' of the foot-rest. The other rope, f', passes through the rear end of the guard-rail c and subjacent post e, and is secured to the seat-frame near the back.

To the upper portions of the ropes f f' is 75 connected a slide or adjustable block, h, and from this block is extended the rope g, the lower end of which is attached to the upper part of the back-frame.

The described construction and combination 80 of parts allow the occupant of the apparatus to throw the same from the form of a chair into the form of a hammock by simply assuming a reclining position and relieving the foot-rest from the pressure of the feet; and the occupant can readily restore the apparatus to its 85 chair form by assuming a sitting posture and pressing on the foot-rest, the latter drawing the back into an upright position by means of the arms b b'.

Having described my invention, what I claim as new, and desire to secure by Letters Patent, 90 is—

1. In a swinging chair, the combination of a seat-frame, a back-frame hinged to said seat-frame, a foot-rest hinged to the front of the seat-frame and provided with rearward projections, and two sets of suspending-ropes connected, respectively, to opposite sides of the chair, one rope of each set passing loosely 95 through the seat-frame, near the front thereof, and attached to the rearward projection of the 100

foot-rest, another rope being attached to the side of the seat-frame, near the back thereof, and the third rope being attached to the upper portion of the back-frame and adjustably connected with the upper portions of the other ropes, substantially as described and shown.

2. A swinging chair composed of a seat-frame, a back-frame hinged to the seat-frame, a foot-rest hinged to the front of the seat-frame, and provided with rearward projections, articulated arms pivoted to the back-frame and rigidly attached to the foot-rest, perforated guard-rails at opposite sides of the seat and across the front, tubular posts supporting said guard-rails, and two sets of suspending-ropes connected, respectively, to opposite sides of the chair, one rope of each set passing through the guard-rails and through the aforesaid front

posts and seat-frame and connected to the rearward projection of the foot-rest, another 20 rope of each set passing through the guard-rails and rear posts and attached to the seat-frame near the back, and a third rope of each set attached to the upper part of the back-frame and adjustably connected to the upper 25 portions of the other ropes, substantially as described and shown.

In testimony whereof I have hereunto signed my name and affixed my seal, in the presence of two attesting witnesses, at Cazenovia, in 30 the county of Madison, in the State of New York, this 15th day of November, 1886.

CORNELIUS SHEPARDSON. [L. S.]
